UNITED STATES PATENT OFFICE

FRANK J. HINDERLITER, OF TULSA, OKLAHOMA, ASSIGNOR TO HINDERLITER TOOL COMPANY, OF TULSA, OKLAHOMA, A CORPORATION OF OKLAHOMA

DRILL COLLAR

Application filed December 26, 1929. Serial No. 416,467.

My invention relates to rotary well drilling apparatus, and more particularly to the drill collar which is interposed between the drill pipe and bit of a tool string.

5 In drilling wells with rotary tools, the working tool or bit is carried at the lower end of a drill pipe and cuttings removed by the bit are flushed from the well with mud-laden fluid circulated through the tool string and 13 well. As greatest torsional strain on the string occurs just above the bit, collars of greater strength and consequently of greater diameter than the drill pipe are interposed at this point for absorbing the exceptional torsional or twisting strain incident to the drilling 15 operation.

The mud-laden fluid passed through the pipe and collar is ordinarily delivered from the bit with sufficient force to scour the bit 20 and lift its cuttings through the well hole about the collar and pipe, but should flow of the fluid be interrupted, mud precipitating from the fluid will settle on the annular shoulder at the top of the collar and form an obstruction known as a mud ring of sufficient 25 volume and density to interfere with removal of the tools.

It is the object of my invention to provide a 20 drill collar whereby formation of such obstruction may be avoided without sacrifice of freedom of circulation of fluid or impairment of strength of the bit coupling, and whereby any formation occurring above the collar during the drilling operation may be 25 removed to permit withdrawal of the tools.

In accomplishing this object, I have provided improved details of structure, the preferred form of which is illustrated in the accompanying drawings, wherein:

40 Fig. 1 is a perspective view of the lower end of a tool string including a drill collar constructed according to my invention, illustrating operation of the tool in a well hole, shown in vertical section.

45 Fig. 2 is an enlarged detail perspective view of the collar, partly broken away for better illustration.

Fig. 3 is a similar view of a slightly modified form of collar.

50 Referring in detail to the drawings:

1 designates a well hole, and 2—3 the pipe and bit of a rotary tool string whereby the hole is drilled in accordance with ordinary practice, the pipe having a coupling 4, and the bit a threaded shank 5 for connection with opposite ends of an interposed drill collar 6. The pipe is tubular and the bit provided with the usual channel (not shown) and port 7 for circulation of mud-laden fluid in accordance with common practice.

55 The collar 6, constructed according to my invention, includes end shanks 8—9 threaded externally and internally, respectively, for attachment to the stem coupling 4 and bit shank 5, and an enlarged body portion 10 having longitudinal grooves 11 rectangular in cross section, formed between spaced ribs 12 extending from end to end of the body, and forming water courses for free flow of the circulating fluid therethrough, the upper 60 end of the body portion 10 being reduced to facilitate lift of the collar through the well, and the upper ends of the ribs 12 being tapered toward their forward edges to form cutting tips 13 for cutting a path through 65 any deposit of mud that may have accumulated in the well above the collar when the tools are being removed from the well hole. The side edges of the ribs are preferably sharp to effect a reaming action on the wall 70 of the well, and the lower ends of the ribs are also preferably tapered toward their forward edges and extended beyond the lower end of the body to form cutting tips 14 for cutting 75 irregular projections from the wall of the well while the drilling is in progress.

80 In the preferred form of structure, the grooves forming the water courses extend in straight lines through the body of the collar, but they may be curved, as shown at 15 in Fig. 3, if desired, to impart an auger action when the tools are in operation.

85 A tool string equipped with a collar constructed according to my invention, may be operated in the usual manner except that circulating fluid delivered from the bit and mixed with cuttings instead of passing upwardly around the collar is ejected through the water courses in the collar with sufficient 90 force to prevent formation of a mud ring 95 100

over the collar while the drilling is in progress. The cutting tips at the lower ends of the ribs remove irregular projections left by the bit on the wall of the hole which might tend to deflect the collar, and the large body of the collar holds the tools straight and insures a straight hole. Should a ring form or cavings accumulate over the collar to an extent which would ordinarily obstruct removal of the tools, fluid circulated through the water courses during removal of the tools will be ejected from the water courses with sufficient force to cut a way for the collar and avoid the sticking which would otherwise occur.

While clearance of the well hole above the collar is the principal advantage desired from use of a collar of my improved construction, the other advantages heretofore noted as incident to this principal feature of improvement add their measure of utility to the tool.

What I claim and desire to secure by Letters Patent is:

1. A drill collar including a body portion having spaced integral ribs rectangular in cross section on its outer face forming grooves rectangular in cross section for forming water courses, and having cutting edges longitudinally of said ribs for reaming the wall of a well hole within which the collar is employed, said ribs having tapered ends forming transverse cutting edges on said ribs.

2. A drill collar including a body portion having spaced longitudinal ribs on its outer face forming water courses therebetween, said ribs having forwardly tapering tips at their upper and lower ends provided with transverse cutting edges, the length of said cutting edges being equal to the depth of the water courses, and an upper shank of less diameter than the body portion including a tapered shoulder joining said shank and the collar.

3. A drill collar comprising a body portion having a tapered and a blunt end and having longitudinally extending parallel grooves in its outer face so as to form cutting edges along one longitudinal edge and both adjacent end edges of said grooves, an internally screw threaded shank of less diameter than and integral with the blunt end of said body portion, a reduced shank integral with the tapered portion of said body portion, and a coupling member carried by the free end of said last mentioned shank.

4. A drill collar comprising a cylindrical body portion having a central bore therethrough and a flat end and a tapered end, longitudinally extending parallel, spaced apart, radially projecting ribs formed integral with the body portion and forming water courses therebetween, cutting edges formed on one of the longitudinal edges and both ends of said ribs, a centrally located internally screw threaded shank of less diameter than and integral with the body portion projecting from its flat end, a hollow cylindrical shank integral with the tapered end, and an internally screw threaded coupling member integral with the free end of said last mentioned shank.

In testimony whereof I affix my signature.

FRANK J. HINDERLITER.
